UNITED STATES PATENT OFFICE.

GEORGE F. GRAY, OF SAN FRANCISCO, CALIFORNIA.

JOINTER FOR ARTIFICIAL-STONE WORK.

SPECIFICATION forming part of Letters Patent No. 361,692, dated April 26, 1887.

Application filed November 11, 1886. Serial No. 218,656. (No model.)

To all whom it may concern:

Be it known that I, GEORGE F. GRAY, of the city and county of San Francisco, State of California, have invented an Improvement in 5 Jointers for Artificial-Stone Work; and I hereby declare the following to be a full, clear, and exact description of the same.

My invention relates to the class of tools or implements which are used in working with 10 artificial stone in the laying of sidewalks, &c.; and my invention consists in a jointer for rapidly and accurately making the joints between the independent blocks of artificial stone.

This jointer is a handled tool having projecting from the plane of its face and on the side thereof a knife or cutter, the outer side of 15 which is perfectly straight.

The object and use of my invention will hereinafter appear.

20 Referring to the accompanying drawings for a more complete explanation of my invention, Figure 1 is a perspective view of my jointer. Fig. 2 is a cross-section of the same. Fig. 3 is a plan by which the method usually employed in laying artificial-stone work may be 25 illustrated, in order to show the use of my jointer.

A is the body of the tool, provided with a handle, D. Projecting from the face of the 30 tool on one side is a knife or cutter, b, the outer side of which is perfectly straight and forms one side of the jointer, while its inner side, which joins the main face, is slightly concaved, though this is not absolutely essential, 35 as it may be straight, if desired.

The tool with a face such as described may be made in any suitable manner. I have here shown a simple construction in which the knife or cutter is formed on the lower edge of a plate, 40 B, the rear end of which takes the handle D, while that portion of the face designated by c, and which may also be slightly concaved, is formed on the lower surface of a piece of block, C, which is secured to the knife-plate by suitable bolts or screws, E.

In order to understand fully the use of this tool I refer now to Fig. 3, from which I will describe the manner or mode usually employed in laying artificial-stone work.

45 F may be supposed to be the bed in which the stone-work is to be laid. It is divided

transversely into main spaces f, separated by minor spaces f', of less width—generally about one-half the width. All the spaces are separated, in the first instance, by guides or boundaries made of straight pieces of scantling, G. The main spaces are first filled in with the concrete or cement, thus forming the blocks the edges of which are defined by the scantling guides. When a block is filled in, the 55 jointer is placed on the edge of the block, with its straight or perpendicular side against the side or edge of the scantling and its concave side against the edge of the cement-work. The tool is then passed along the scantling, its 60 straight side close against it. The effect of this is to make the joint with the concave side of the knife, the remaining face, c, of the tool properly rounding it. After these main blocks of artificial stone have sufficiently hardened 65 the scantlings are removed, because they are no longer needed for guides, as the hardened edges of the main blocks serve this purpose. The intermediate minor spaces are then filled in with artificial stone right up to the edge of 70 the main blocks. The jointer is again taken, but in a reverse direction, so that its straight side now comes against the previously prepared edge of the main block, while its opposite side moves along the fresh material of the 75 minor block, thus making its joint the same as the main block. It will thus be seen that the tool makes but one joint at a time.

I am aware of the existence of tools for stamping the margins of cement-work, and 80 also for marking out the smaller divisions of the blocks or stones, and which are known as “creasers.” I do not wish my invention confounded with these tools, as it is not used for the same purpose, and the purpose for which 85 it is used requires such a change of construction in the tool as to render it adapted for its use, without which change it could not be used for the purpose of jointing. To illustrate this I refer particularly to a “creaser” sometimes 90 used for marking the smaller divisions of the main stone. This creaser has projecting from the center of its face a knife which is in cross-section what may be termed a “hatchet shape,” or approximately that of an inverted isosceles 95 triangle having its sides concave.

It is obvious that such a tool could not be

used for a jointer, for the reason that it has not a straight edge, which is absolutely essential for working against the straight side of the scantling guide and against the previously hardened and prepared joint of the alternate blocks, as I have described. For the same reason the stamp sometimes used, and which has a knife on one edge, but with its outer side beveled and not straight, cannot be used as a jointer.

Having thus described my invention, what I claim as new, and desire to secure by Letters Patent, is—

A jointer for artificial-stone work having projecting from one side only of the plane of its face a single knife or cutter, having its outer side straight and forming one side of the tool and its inner side concave and joining and continuing the remaining face of said tool, substantially as herein described.

In witness wherof I have hereunto set my hand.

GEORGE F. GRAY.
